UNITED STATES PATENT OFFICE

JACOB L. KLEINMAN, OF NEW YORK, N. Y.

NET HOLDER

Application filed April 26, 1932. Serial No. 607,560.

This invention relates to tennis net holders and more particularly to table tennis net holders, for use in playing what is known as ping-pong tennis.

A primary object of this invention is to provide a net holder so constructed that the several parts thereof can be stamped of thin pieces of sheet metal and so configured as to have substantially the same strength as parts made of heavy castings or of comparatively thick material.

A further object of the invention is to provide a net holder having means for readily adjusting the tension of the net.

Another object is to provide a net holder having means for evenly adjusting the tension of the net.

A still further object is to provide a net holding assembly consisting of a table clamp, a movable net holder and a member disposed at the top of the table holder adapted to engage the net holder and operating to control the movement of the net holder.

Still a further object is to provide a net holding assembly including a table clamp portion having a movable plate arranged to engage the underside of the table, thus preventing injury to the table when the clamping screw forming part of the assembly is turned tight.

Another object is to provide a net holding assembly consisting of a table clamp and a movable net holder wherein said clamp and holder are provided with interfitting ribs and grooves, whereby the net holder is positively guided in its movements during the adjustment thereof.

Still another object is to provide a net holder having a hinged member for holding the net.

It is also an object of this invention to provide a net holding assembly consisting of a table clamp and a net holder, wherein said table clamp has portions projecting above its

surface for the purpose of holding and guiding the net holder.

Still a further object is to provide a net holding assembly so constructed as to permit the use of a very thin material, thereby reducing the weight of material required, and of a type that is practical, durable, useful, convenient to operate, simple and economical to manufacture.

Other objects and advantages of the present invention will appear from the description thereof to follow taken in connection with the accompanying drawing in which—

Fig. 1 is a side view of an assembled table tennis net holding set embodying my present invention.

Fig. 2 is a view taken along the line 2—2 of Fig. 1, showing in more detail the structure of the movable plate portion which is to engage the underside of the table top.

Fig. 3 is a cross-sectional view of a portion of the net holder taken along line 3—3 of Fig. 1.

Fig. 4 is a front view of a portion of the table clamp and of the net holder.

Fig. 5 is a modified form of the structure shown in Fig. 4.

Fig. 6 is another modified form of the construction shown in Fig. 4.

Fig. 7 is a cross-sectional view along the line 7—7 of Fig. 6.

Fig. 8 is a modified view of the upper portion of the net holder showing how the net may be attached directly to the net holder, and

Fig. 9 is a modified view of a portion of Fig. 1.

Referring to the drawing; 5 indicates the clamp which fits over a table (not shown), said clamp being provided with a back portion 6 and a bottom portion 7. A bead, rib or tongue 8 is formed on the top, back and bottom portions of said clamp. The edges 9 of the back portion 6 and of a part of the portions 5 and 7 are flared to one side and form

flanges 9'. Due to such construction the clamp can be made considerably strong and of comparatively thin material, whereby the weight of the assembly is reduced and thereby the manufacturing cost diminished. The bottom portion 7 is provided with a hole 10, the edge 11 being struck upwardly thereby providing a larger surface for threading. A plate 13 formed with an opening 14 is slidably mounted on the back portion 6, said plate 13 is also provided with a depression 15, said depression is provided with a counter-sunk portion 16. A screw 17 is inserted into hole 10 and engages portion 16 and on proper rotation pushes plate 13 toward the table; due to the depression 15 the plate 13 possesses great strength and when forced against the table, the surface 18 engages the underside of the table top, the screw 17 being thus kept away from direct contact with any part of the table, and injury to the table avoided that may otherwise be done to the table when attaching the clamp. The upper portion of clamp 5 is provided with offset portions 19, said offset portions 19 being bent over a slidably attached member 20, said member 20 being provided with a bead or groove 21 fitting loosely over head or rib 8 of clamp 5, one of the offset portions 19 is provided with a hole whose edge 22 is pushed through in order to provide a larger surface for threads to receive a screw 23, the end of said screw 23 engages one of the sides of member 20, said member 20 is at one of its ends provided with an upstanding flange 24, preferably formed by a bend at a certain place so that 20 and 24 are made of one piece; of course same can be made of two pieces if so desired; the edges 25 of flange 24 are flared away and bend to one side as at 26 (Fig. 3) thus making the whole member 20 a strong and rigid structure. The top portion of flange 24 is bent into a U-shape 27 wherein a member 28 is placed, the flaps 29 are provided with holes 30, a pin or rivet is then inserted, passing through an opening (not shown) of member 28, permitting said member 28 to hinge upon said pin; said member 28 is also provided with holes or openings 31 for the purpose of having strings of a net (not shown) attached thereto, this member 28 may be stamped or bent of any suitable material. From the above description it is evident that when the clamps are attached to each side of the table, the net tightened to members 28, the screw 23 is then loosened, member 20 pulled away thus tightening the net, member 28 will hinge to even the tension of the upper and lower edge portion of the net, giving same a complete straight form. In case the net should happen to be too tight, member 28 will spring and give a little, thus perfecting the tension of the net. The screw 23 is then tightened and there we have a perfect, practical, adjustable net holder.

With reference to modified form Fig. 5, clamp 5 has two beads or ribs 8 instead of one (see Figs. 1 and 4), the edges 32 form the offset or inclined portions 19. Member 20 is shaped all the way through the same way as flange 24 (see Figs. 1 and 3). Screw 23 is also included and the result is practically the same as that of Fig. 1, but, whereas in Figs. 1 and 4 groove 21 of member 20 slides over bead or rib 8 of clamp 5, in this modified form 5, the round-shaped inner surface 33 of member 20 slide over the beads or ribs 8, while the inclined edges 34 are housed in channels or grooves 35.

With reference to modified form Figs. 6 and 7, a hole 36 is formed in bead 8 of clamp 5, and bead 21 of member 20 is provided with a slot 37, screw 23 is then passed through said slot and inserted into hole 36, when said screw 23 is loosened, member 20 can then be moved there and back, but when screw 23 is tightened shoulder 38 will press upon the edges 39 of the slot 37, thereby preventing the movement of said member 20, thus we have the same effect as of Fig. 1.

It will be noted that on account of the bead construction the end 23' of screw 23 will not touch or injure any part of the table.

With reference to Fig. 8, this modified form shows flange 24 without a U-shape 27 and without member 28 but instead, said flange 24 is formed with a hole 38' through which string 39' of a net (not shown) is inserted, the remainder of said string is then wound and tightened around said flange 24 at inclined sections 40 to hold said string 39' tight to flange 24 as at 41.

With reference to Fig. 9 this modified form shows member 28 being hingeably connected to a screw element 42 said element 42 is slidably mounted in opening 43 of flange 24, a thumb screw or nut 44 is rotatably mounted on said screw element 42 so that when, during play, the net loosens or sags, a few turns of nut 44 will again tighten the net. This particular structure may be used to great advantage in regular tennis net sport.

From the above description it is evident that the principal idea of this invention is to solve the question of how to manufacture for a reasonable price a good, solid, strong, serviceable net holder. Applicant during his experiments, has found that the groove and tongue bends as suggested and employed in the making of this invention, in addition to guiding each other when assembled and being adjusted, also reinforce and stiffen the parts, therefore a much thinner material may be used, greatly reducing the weight of each set of net holders, thereby greatly reducing the cost of such net holders, resulting in being able to sell same for a much cheaper price to the trade and to the consumer.

Although I have mentioned in describing my invention certain parts that may be used,

yet I desire it to be understood that various modifications and various changes in detail may be resorted to without departing from the spirit of the invention.

5. I claim:

1. A net holder for table tennis and similar games, comprising a substantially U-shaped member one of whose arms is adapted to engage the top surface of a table, a screw threaded through the other arm, a plate guided by said member and engaged by said screw, said plate adapted to engage the underside of a table, a net anchoring element movably disposed on the first mentioned arm, both said member and element made of sheet metal and at least a portion of said member and said element being corrugated to increase the strength thereof and in such manner that the corrugation in said element interfits with the corrugation in said first mentioned arm, whereby said element is guided in its adjusting movements on such arm by said interfitting corrugations, and means for securing said element in adjusted position.

2. A net holder for table tennis and similar games, comprising a substantially U-shaped member one of whose arms is adapted to engage the top surface of a table, means associated with the other arm and adapted to engage the underside of a table, a net anchoring element movably associated with said first mentioned arm, both said member and element made of flat material and at least a portion of said member and said element being corrugated to increase the strength thereof and in such manner that the corrugation in said element interfits with the corrugation in said first mentioned arm, whereby said element is guided in its adjusting movements on such arm by said interfitting corrugations, and means for securing said element in adjusted position.

3. A net holder as set forth in claim 2, wherein said last mentioned means comprises a screw threaded into an upwardly extending portion of the first mentioned arm.

4. A net holder as set forth in claim 2, including a net-engaging member pivotally mounted on said anchoring element.

5. A net holder comprising a mounting member, an upstanding post and a hingeable net supporting member connected to said post and operating to adjust the tension of the upper and lower edges of the net.

6. In a net holder for table tennis and similar games, comprising a corrugated U-shaped member, a corrugated net supporting member associated with said U-shaped member, and means co-operating with a plate guided by said U-shaped member for securing the latter to a table top.

7. In a net holding assembly for table tennis and similar games, comprising a U-shaped member, a net supporting element associated with said member, one portion of

said member adapted to engage the surface of a table top, a plate associated with said member and adapted to engage the underside of said table top and means for securing said plate and said member to said table top, said element being adjustable independently of said means.

8. In a net holding assembly for table tennis and similar games, comprising a U-shaped member having an adjustable element, a plate associated with said member and being engaged by said element and adapted to be forced against a table top surface, thereby securing said member to said table top, a net supporting member associated with said first mentioned member and adapted to be independently adjustable thereon, said plate having a depressed portion to increase the strength thereof.

9. A net holder for table tennis and similar games comprising a U-shaped member and a movable net supporting element, at least a part of the edge portions of said member and element being of acute angular shape and interfitting with each other so as to prevent longitudinal displacement, means for adjusting the movements between said element and said member, a plate having an irregular surface associated with said U-shaped member and means for securing said plate and said member to a table top.

10. A net holder comprising an upstanding post, means for securing said post to a playing surface, a net-supporting member hingeably connected to an element, sail element loosely mounted in said post, and means for adjusting the movement of said element in said post, thereby adjusting the tension of the net.

11. A net holder comprising a mounting member, an upstanding post, and a hingeable net supporting member the ends of which are secured to the upper and lower strands of a net and being connected to said post and operating to adjust evenly the tension of the upper and lower edges of the net, said hingeable member being yielding to limit the tension in the net.

12. In a net holder as set forth in claim 2, wherein said means comprises an upwardly extending portion struck from the body of said arm.

13. A net holder for table tennis and similar games, comprising a mounting member having one arm engaging a playing surface, fastening means for securing said member to said playing surface, a net supporting element slideable on said arm in such manner that when said member and element are in operative position said element does not directly engage said playing surface and may be adjusted independently of said fastening means.

14. A net holder for table tennis and similar games, comprising a mounting member

having one arm engaging the surface of a table top, fastening means for securing said member to said table top, a net supporting element slideable on said arm in such manner that when said member and element are in operative position said element does not directly engage said surface of said table top and may be adjusted independently of said fastening means.

In testimony whereof, I hereunto affix my signature.

JACOB L. KLEINMAN.
